US0D1056613S

(12) **United States Design Patent** (10) **Patent No.:** **US D1,056,613 S**
(45) **Date of Patent:** **** Jan. 7, 2025**

(54) **PORTABLE BLENDER**

(71) Applicant: **Cheng Shi**, Shenzhen (CN)

(72) Inventor: **Cheng Shi**, Shenzhen (CN)

(**) Term: **15 Years**

(21) Appl. No.: **29/888,913**

(22) Filed: **Apr. 6, 2023**

(51) **LOC (15) Cl.** 31-00

(52) **U.S. Cl.**

USPC **D7/378**

(58) **Field of Classification Search**

USPC D7/300, 305-321, 368, 372, 376, 377, D7/378, 379, 380, 381, 382, 383, 384, D7/385, 386, 387, 412, 413, 414, 415, D7/669, 672, 673, 674, 678, 679, 693, D7/694, 695, 696, 697, 510, 532

CLAIM

The ornamental design for a portable blender, as shown and described.

DESCRIPTION

FIG. 1 is a first perspective view of a portable blender showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the portable blender that form no part of the claimed design.

1 Claim, 8 Drawing Sheets
